COAT HANGER ADAPTED TO BE SEWED
INTO THE SHOULDER LINING OF
CLOTHES

Rudolf Senn, Basle, Switzerland

Application October 2, 1945, Serial No. 619,837
In Switzerland November 6, 1944

5 Claims. (Cl. 2—271)

1

The invention relates to a coat-hanger adapted to be sewed into the shoulder-lining of clothes. According to this invention, the coat-hanger is composed of a strip of elastic, flexible material, one of its broad sides being taken up by an uninterrupted row of adjoint-pieces, the intervening space being so small that any bending of the strip towards this side is prevented. This strip should preferably consist of rustless spring-metal, for instance, spring-steel or spring-bronze. The adjoint-pieces may be little plates of metal or artificial resin, and similar substances, attached in some way or other to the strip, for instance, by means of rivets.

A coat-hanger as described above may freely be bent towards the broad side lying opposite the adjoint-pieces, whereas it assumes the state of a stiff rod in respect to bendings towards the other side as soon as the adjoint-pieces push against each other and, in this position, it may be used as an ordinary coat-hanger. If this coat-hanger is laid into the shoulder-lining of an article of clothing it is possible, in the case of the last mentioned position, i. e., when the adjoint-pieces are lying downwardly, to hang up this garment on the coat-hanger. However, if the coat-hanger is turned about by 180° around its longitudinal axis, whereby the adjoint-pieces are caused to lie upwardly, it is comfortably fitted to the garment by correspondingly bending the neck-and shoulder-parts and thus the hanger is not in the way and is not objectionable to the wearer.

According to a further object of the present invention, the strip, together with the adjoint-pieces, can be brought into a loose stuff-covering, sufficiently spacious to allow the strip to be turned from the outside, whereupon this stuff-covering can, as already mentioned be sewed into the shoulder-lining of a garment. It is advisable to, subsequently, attach the suspension-loop to the stuff-covering, and to lead it through one or two slits of the shoulder-lining, whereby the loop is located in the normal position for the suspension of the garment.

An embodiment of this invention is described below, and supplementary information is given by the enclosed sketch.

Fig. 1 shows a lateral view, and

Fig. 2 a ground-plan of a coat-hanger, according to the present invention.

Fig. 3 is a front elevation showing on a smaller scale, how the coat-hanger, in the same position as presented in Fig. 1, is placed into a coat or an overcoat in a manner approximately corresponding to the form, when wearing this garment.

2

Fig. 4 is a front elevation showing the same garment carried by hand.

Fig. 5 is a front elevation showing the suspension of the same garment, the coat-hanger having been turned about by 180°.

According to Figs. 1 and 2, the coat-hanger is composed of a strip *a* of elastic, flexible material, for instance, spring-steel, and a number of small plates *b* lying in succession at a small intervening space, each of which is connected with the strip *a*, by means of a rivet *d*. The intervening space between the single small plates *b* is so small that the neighbouring edges of the plates *b*, when bending the strip in an upward direction, push against each other and thus prevent further bending, whereby the coat-hanger approximately assumes a curved form as shown in Fig. 5, and acquires the state of a rigid, bent rod, thus assuring its use as a coat-hanger. According to Fig. 5, a strip *a*, together with the adjoint-pieces *b*, is located in a stuff-covering *e*, this latter being sufficiently spacious to allow the strip to be turned about from the outside, around its longitudinal axis. Furthermore, a suspension-loop *f* is sewed on to the stuff-covering, this loop being led through two slits *g* in the shoulder-lining of the garment *h* and, in this manner, the coat-hanger and the garment may be suspended to the loop, for instance, in the position of the peg *i*, shown in 30 transverse section.

When the garment *h* is worn, it is possible to turn the strip *a*, together with the adjoint-pieces *b* around its longitudinal axis by 180°, by means of thumb and forefinger, holding the garment on 35 both shoulder-parts, whereby the small plates *b* lie upwardly, as shown in Fig. 1. As shown in Fig. 3, the garment, in this form, is freely adapted to the shoulder- and neck-parts of the person wearing the garment. Furthermore, a free adaptation of the coat-hanger for further use takes place in the same form, for instance, when carrying it by hand, as shown in Fig. 1.

The length of the coat-hanger can be adapted to the shoulder-width of the garment; it is also 45 possible to select a weaker or stronger coat-holder, according to the character of the garment, the latter, for instance, in the case of heavy winter-overcoats, whereas, otherwise, a weaker, and particularly supple form is to be recommended. A 50 coat-holder of such nature is adapted to press closely to the neck- and shoulder-form of the person wearing it and, therefore, even in the case of light material, the presence of the coat-holder in the shoulder-lining is neither noticeable, nor 55 felt as being inconvenient.

I claim:

1. A coat-hanger adapted to be sewed into the shoulder-lining of a garment, composed of an elastic, flexible strip, a broad side of this strip being taken up by an uninterrupted row of adjoint-pieces, their intervening space being so small that they limit a bending of the strip towards this side.

2. A coat-hanger adapted to be sewed into the shoulder-lining of a garment, composed of an elastic, flexible strip of rustless spring-metal, a broad side of this strip being taken up by an uninterrupted row of adjoint-pieces, their intervening space being so small that they limit a bending of the strip towards this side.

3. A coat-hanger adapted to be sewed into the shoulder-lining of a garment, composed of an elastic, flexible strip, a broad side of this strip being taken up by an uninterrupted row of adjoint-pieces, such adjoint-pieces being composed of small plates attached to the strip, the intervening space between these pieces being so small that they limit a bending of the strip towards this side.

4. A coat-hanger adapted to be sewed into the

shoulder-lining of a garment, composed of an elastic, flexible strip, a broad side of this strip being taken up by an uninterrupted row of adjoint-pieces, their intervening space being so small that they limit a bending of the strip towards this side, a stuff-covering loosely wrapping up the strip and the adjoint-pieces, this stuff-covering being sufficiently spacious to allow the strip contained therein to be turned about from the outside.

5. A coat-hanger adapted to be sewed into the shoulder-lining of a garment, composed of an elastic, flexible strip, a broad side of the strip being taken up by an uninterrupted row of adjoint-pieces, their intervening space being so small that they limit a bending of the strip towards this side, a stuff-covering loosely wrapping up the strip and the adjoint-pieces, this stuff-covering being sufficiently spacious to allow the strip contained therein to be turned about from the outside, and a suspension-loop adapted to be drawn through slits of the shoulder-lining and attached to the middle part of the stuff-covering.

RUDOLF SENN.
